UNITED STATES PATENT OFFICE.

DANVILL W. STARRETT, OF SAN FRANCISCO, CALIFORNIA.

PUMP OPERATED BY COMPRESSED AIR.

No. 876,849.

Specification of Letters Patent.

Patented Jan. 14, 1908.

Application filed April 27, 1904, Serial No. 205,128. Renewed April 12, 1907. Serial No. 367,803.

To all whom it may concern:

Be it known that I, DANVILL W. STARRETT, a citizen of the United States, residing at San Francisco, in the county of San Francisco 5 and State of California, have invented certain new and useful Improvements in Pumps Operated by Compressed Air, of which the following is a specification.

My invention relates to improvements in 10 pumps operated by compressed air, the object of my invention being to provide a simple form of pump operated by compressed air by means of which water may be elevated to any height by means of compressed air at any 15 pressure greater than the atmosphere.

My invention belongs to that class described and claimed by me in United States Letters Patent granted to me May 29th, 1906, No. 821,677 in which there is provided in the 20 water discharge pipe a check valve, and to said discharge pipe above the check valve there leads a branch from the compressed air pipe, in which branch the opening is sufficiently large, having regard to the height of 25 the discharge pipe and the pressure of the compressed air, to admit a sufficiently large proportion of air to water to distribute the water through the whole length of the pipe to such an extent that the weight of the entire 30 amount of water shall not overbalance the pressure of the compressed air; whereby when water escapes from the top of the discharge pipe the pressure of the compressed air may be utilized to force water through 35 the check valve into the discharge pipe to supply the place of that which has been discharged from the top thereof.

This invention consists of a simple construction for effecting the above results. 40 An especial object of my present invention is to provide such a construction by means of which the air after being utilized to force water through the check valve may be introduced into the water discharge pipe to assist 45 in lifting the water.

In the accompanying drawings, Figure 1 is a vertical section of the apparatus, certain of the pipes however being shown in side elevation; Fig. 2 is a side elevation of the upper 50 portion of the apparatus; Fig. 3 is a horizontal section on the line A—A of Fig. 1; Figs. 4 and 5 are views similar to Figs. 1 and 2 of a modified form of the apparatus; Fig. 6 is a vertical section of the reducing valve.

55 Referring to the drawing, 1 represents the

compressed air pipe, 2 the water discharge pipe and 3 the water suction pipe.

4 represents a common steam pump comprising a steam cylinder 5 and a pumping cylinder 6. In the present instance the steam 60 pump is preferably operated by means of compressed air. The piston 7 and 8 in these cylinders are of substantially the same diameter and are connected by a piston rod 9.

10 is the valve chamber having the valve 65 11 therein operated from the piston rod 9 by the lever 12, links 13 and rod 14.

15 represents a chamber divided into upper and lower portions by a horizontal partition 16, the lower portion being again divided 70 by a vertical partition 17 into compartments 18 and 19, connected respectively with the upper and lower ends of the pumping cylinder. These compartments contain inlet valves 20, 21. The upper portion or compartment 22 contains check valves 23, 24, communicating respectively with the compartments 18, 19.

25 represents a branch or jet pipe leading from the compressed air pipe to the water 80 discharge pipe and having therein an adjustable check valve 26. Beyond said check valve there is provided a nozzle 27 which discharges the compressed air into said branch pipe 25 opposite to the entrance of an exhaust pipe 28 leading from the exhaust chamber 29 of the pump and having therein a pet-cock 30.

The operation of the apparatus is as follows. Supposing the parts to be in the position shown in Fig. 1, the air entering the upper portion of the cylinder 5 forces the piston 7 downwards, likewise forcing down the piston 8 and drawing water from the pipe 3 through the valve 20 into the chamber 18 and thence to the upper end of the pumping cylinder 6. Upon the return stroke of the piston caused by the admission of compressed air to the lower end of the cylinder 5, the water in the upper portion of the pumping 100 cylinder is forced back into the compartment 18, and thence through the valve 23 into the compartment 22. At the same time water is being drawn through the valve 21 into the compartment 19 and thence into the lower 105 end of the pumping cylinder, which, again, on the return stroke of the piston, is forced through the valve 24 into the chamber 22. During the whole of this operation compressed air is also passing through the branch 110

pipe 25 into the water discharge pipe, and it is only when the amount of air so forced through said branch or jet pipe is sufficient to distribute the water along the discharge pipe 5 to such an extent that the pressure of the whole of the water therein upon the valves 23, 24 is less than the pressure of the compressed air, that any water passes through said valves. As soon as water is discharged 10 from the top of the discharge pipe by reason of the continued flow of the compressed air into the bottom of said discharge pipe, then immediately the pump begins to work and water is forced through the valves 23, 24, 15 into the discharge pipe to supply the place of the water that had been discharged from the top of said pipe. The exhaust air of the pump after performing its office of driving the piston is permitted to flow into the water 20 discharge pipe 2, and it is in order to avoid any back pressure that the nozzle 27 is provided, since it assists the passage of the air from the exhaust chamber to said water discharge pipe. By this means the air of the 25 pump is utilized to lift the water in the water discharge pipe.

Figs. 4, 5 and 6 show a modification in which the piston of the steam cylinder is of greater area than that of the pumping cylinder. In this case therefore it is necessary to 30 reduce the pressure of the air supply to the steam cylinder. This is done by means of the throttle valve 31, shown in detail in Fig. 6. It would be possible to make the piston of the 35 steam cylinder of less area than that of the pumping cylinder in like manner except that in this case the throttle valve should be placed in the branch pipe leading from the compressed air pipe to the water discharge pipe. 40 The pet-cock 30 can be used to reduce the pressure very low, if desired, when economy is not of the first importance.

I do not claim herein matter claimed by me in a copending application Serial No. 45 367,071, filed April 8th, 1907, confining myself in the present application to the specific claims here made.

I claim:

1. In an apparatus of the character described, the combination of the compressed air pipe, the water discharge pipe, the inlet valve for the water, the check valve therefor at the bottom of said water discharge pipe, a pump discharging into the space between the 50 inlet and check valves and having a piston operated by the compressed air, a passage from the compressed air pipe to the water discharge pipe sufficiently large in relation to the compressed air pressure and the height 55 of the discharge pipe to distribute the water 60 therein sufficiently to reduce the weight of

the water upon the check valve below the compressed air pressure whereby said pressure can operate to pump water through said check valve, and an exhaust pipe leading to 65 said passage from the exhaust chamber of the pump, substantially as described.

2. In an apparatus of the character described, the combination of the compressed air pipe, the water discharge pipe, the inlet 70 valve for the water, the check valve therefor at the bottom of said water discharge pipe, a pump discharging into the space between the inlet and check valves and having a piston operated by the compressed air, a passage 75 from the compressed air pipe to the water discharge pipe sufficiently large in relation to the compressed air pressure and the height of the discharge pipe to distribute the water therein sufficiently to reduce the weight of 80 the water upon the check valve below the compressed air pressure whereby said pressure can operate to pump water through said check valve, an exhaust pipe leading to said passage from the exhaust chamber of the 85 pump, and a nozzle in said passage to draw the air along said exhaust pipe, substantially as described.

3. In an apparatus of the character described, the combination of a compressed air 90 pipe, a water discharge pipe, an inlet valve, a check valve at the bottom of the water discharge pipe, and a pair of cylinders having pistons therein of unequal diameters, said pistons being connected to work in unison, 95 one of said cylinders being connected with the compressed air pipe to act as a compressed air motor, and the other cylinder being connected with the chamber between the inlet and check valve to act as a pump, a valve 100 reducing the pressure of the compressed air and suitably located in correspondence with the inequality of the pistons to cause the pressure of the piston operated direct by the compressed air to balance the water pressure, 105 and a passage from the compressed air pipe to the water discharge pipe sufficiently large in relation to the height of the discharge pipe and the compressed air pressure to distribute the water in said discharge pipe sufficiently 110 to reduce the weight of the water upon the check valve below the compressed air pressure, whereby said pressure can operate said pistons to force water through said check valves, substantially as described.

In witness whereof I have hereunto set my hand in the presence of two subscribing witnesses.
